UNITED STATES PATENT OFFICE.

HENRY CHARLES EDEN MALET, OF BRIGHTON, COUNTY OF SUSSEX,
ENGLAND.

GUN-CARRIAGE.

SPECIFICATION forming part of Letters Patent No. 339,795, dated April 13, 1886.

Application filed April 21, 1885. Serial No. 162,978. (No model.) Patented in England February 12, 1884, No. 3,149, and May 22, 1884, No. 8,032.

To all whom it may concern:

Be it known that I, HENRY CHARLES EDEN MALET, a subject of the Queen of Great Britain, residing at Wilbury Lodge, Brighton, in the county of Sussex, England, have invented a new and useful Improvement in Gun-Carriages, (for which I obtained Letters Patent in Great Britain as follows: No. 3,149, dated February 12, 1884, and No. 8,032, dated May 22, 1884,) of which the following specification is a full, clear, and exact description.

The object of my invention is to produce a field-gun carriage having attached thereto a recoil device and a shield.

15 Figures 1, 2, 3, and 4, Sheet 1, represent different views of a field gun and carriage with my improvements applied thereto. Fig. 1 is a side elevation showing gun in firing-position; Fig. 2, an end elevation, and Fig. 3 20 a plan of same. Fig. 4 is a side elevation of gun limbered up for traveling. Fig. 5, Sheet 2, is a sectional elevation of the same, showing the cylinder enlarged and the valve connected thereto.

25 In Figs. 1 and 4 one wheel is removed, in order to show more clearly the arrangement of the carriage.

The same letters refer to the same parts in each figure.

30 The trail is composed of two girders or cheeks, *a a*, united by top and bottom plates, *b b'*, and terminating in a shoe and eye, *c*, to engage with the hook on the limber in the usual way. The axle-tree is a tube, *d*, passing through holes in the cheeks of the trail, and firmly keyed or fastened therein. Diagonal stays *d'* may also be provided, if necessary. Solid ends are provided to the axle-tree for the wheels to run upon.

40 The gun *e* is provided at or about its center of gravity with trunnions *e' e'*, which may be placed centrally with its axis, as shown in Fig. 3, or, if preferred, somewhat below the center, as in Figs. 1, 2, and 4. To these trunnions links *f f* are attached, by means of which the gun is hung from the cheeks of the trail, the said cheeks being carried up the necessary height, as shown, and provided with bearings and caps *g g*, to enable the gun to be 45 removed from the carriage when required. By keeping the trunnions low, as in Figs. 1, 2, and 4, it is not necessary to carry the cheeks

of the trail up so high as when the trunnions are central. To the under side of the breech of the gun a rack, *h*, curved to a radius from 55 the center of the trunnions *e' e'* is firmly attached. Two light suspension-links, *i i*, equal in length to the links *f f*, are hung from bearings *i' i'* on the cheeks of the trail, and carry at their lower ends by means of pivots a flat 60 box or sheath, *j*, through which the rack *h* passes. This sheath is provided with a pinion, *k*, gearing into the teeth of the rack *h*, and upon the shaft of this pinion a worm-wheel, *l*, is keyed, which is capable of rotation 65 by means of the tangent screw and hand-wheel *m*.

The elevation and depression of the gun is accomplished by turning the hand-wheel. The position of the center line of the gun 70 when at an elevation of twenty degrees and a depression of seventy degrees with the horizontal arc is shown in Fig. 1. The links *i i* not only support this elevating apparatus, but they also preserve the parallelism of the gun 75 when it swings back under the influence of the force of recoil. To check the velocity of this swinging motion, and to restrain it within proper limits, a cylinder, *n*, is provided. It is hinged to the axle-tree by the tube *o*, and 80 its piston-rod head *p* is pivoted to the gun under the breech. This cylinder is filled with oil or other suitable fluid, and an orifice or valve, *n'*, (see Fig. 5, Sheet 2,) capable of adjustment, is provided in the piston or otherwise, so that the resistance offered to the passage of the piston through the fluid can be 85 regulated as desired.

The action of the apparatus is as follows: When the gun is fired, the force of recoil tends 90 to cause the gun to swing backward and upward in the arc of a circle of a radius equal to the length of the suspension-links, and at the same time to pull the piston through the fluid in the cylinder *n*, the valves of the said cylinder being so adjusted that when the gun has ceased to move in relation to the carriage it will be in about the position indicated by the dotted lines *q q*. Thus the force of recoil will have raised the weight of the gun through a 95 certain height, and at the same time encountered and so far overcome the resistance of the fluid in the cylinder, which, however, being adjusted to allow of no further com-

pression, arrests the movement of the gun after it has traversed an arc of from, say, about seventy degrees to ninety degrees, and causes what remains of the strain of recoil to be now transferred as a pressing or pushing force to the gun-carriage. As the cylinder will offer a resistance to the descent of the gun, it will come back slowly, and will be stopped by the piston abutting on the end of the cylinder exactly in the position it was in when fired. The gun, when adjusted to the required angle, may therefore be fired any number of times without affecting such adjustment. The strains upon the carriage caused by recoil will be compounded principally of the pull of the cylinder upon the axle-tree, and the pull upon the bearings $g g$ through the links ff as the gun rises in the arc of a circle. This latter pull causes a strain of a gradually-increasing character, which theoretically commences from zero if the pressure caused by the dead-weight of the gun be neglected. A small portion of the latter strain may probably be taken by the links ii . It will thus be seen that there is no sudden blow or shock communicated to the carriage on the firing of the gun, and the parts of the carriage may therefore be constructed as lightly as is possible consistent with sufficient strength being retained to resist the strains and shocks incident to traveling.

When the gun is to be limbered up for traveling, it is only necessary to depress the breech as far as possible by means of the elevating apparatus, when it will present the appearance shown in Fig. 4; and in order to relieve the links ff from the strain of the weight of the gun when in that position a small sealing, r , working in a slide, s , is forced up under the gun near its center of gravity by means of a screw and hand-wheel, t , or other suitable device.

In order to protect the men working the gun in action from musketry-fire, the axle-tree seats uu are formed of sheet-steel, and are capable of rotation about the axle-tree into a vertical position, v , Figs. 2 and 3. The back rail is hinged, so that it can be turned up vertically in line with the seat, and the side rail w is also hinged so that it can be folded flat against the seat, and the foot-rest x , being also hinged, hangs vertically of its own accord when the seat is thus rotated. A steel plate, y , is then hung on the back rail, and a similar plate, y' , on the hinge of the foot-rest. Suitable stops, zz , are provided on the axle-tree, to limit the rotation of the seat between the vertical and horizontal positions by means of projections $z'z'$, which abut against the stops zz . The action of gravity will retain the seat in the vertical position; but to fix it in the horizontal position a sliding bolt, (not shown in the drawings,) passing through holes in the stops zz and projections $z'z'$, may be employed, or any other device which will answer the same purpose.

To retain the back rail in the vertical po-

sition when the seat is vertical, hooks $z^2 z^2$ may be provided to engage with the edge of the seat.

The ends of the side rails fit into sockets in the back rail when in the ordinary position for traveling, as shown in the drawings.

Figs. 2 and 3 show one axle-tree seat in the ordinary position and the other when arranged as a shield. The axle-tree seats u and the loose plates $y y'$ thus protect the space on each side of the gun. The space under the gun is protected by the trail and the plate b' , which is turned up vertically in front of the standards on the trail, as shown clearly in Figs. 1 and 2. By this means the only part left unprotected is the small space immediately over the gun; but this must be left open to allow for sighting.

The plates y and y' may be carried on the limber or ammunition-wagon, as may be found most convenient; or all the plates for a battery may be carried on a spare limber.

The axle-tree seats, as shown, are provided with springs to render them easier for the riders, and ammunition-boxes may be fitted to them in the ordinary way, if required.

I do not claim as part of this invention the shields herein represented for the protection of the gunners, as said shields are a part of the invention which is the subject of my application for United States Patent, Serial No. 182,656, filed November 13, 1885.

Having thus described my invention, I desire to claim—

1. The combination, with the gun and its carriage, of links by which the gun is suspended from the carriage and a hydraulic recoil cylinder and piston pivotally connected with the gun and carriage, substantially as and for the purpose herein described.

2. The combination, with the gun and its carriage, of links by which the gun is suspended from the carriage and a hydraulic cylinder and piston connected pivotally with the gun and with the axle of the carriage, substantially as and for the purpose herein described.

3. The combination, with the gun and its carriage, of links by which the gun is suspended from the carriage, a rack attached to the gun, a pinion gearing with said rack for elevating the gun, a box through which said rack passes and which carries said pinion, and links which suspend the said box from said carriage, substantially as herein set forth.

In testimony that I claim the foregoing I have hereunto set my hand this 15th day of November, 1884.

HENRY CHARLES EDEN MALET.
